SEPARATION PROCESS

Horace M. Weir, Wynnewood, Pa., assignor to The
United Gas Improvement Company, a corpora-
tion of Pennsylvania

Application July 11, 1941, Serial No. 401,966

15 Claims. (Cl. 252—346)

This invention pertains to the recovery of valuable hydrocarbons from tar formed during the production of combustible gas by processes involving the pyrolytic decomposition of hydrocarbon oil with or without the aid of catalysts.

Various processes are known for the manufacture of combustible gas such as carburetted water gas and oil gas wherein a petroleum oil such as crude oil or a fraction or fractions thereof, for example, gas oil, residuum oil, etc., is pyrolytically decomposed.

In such processes the gas leaving the gas-making apparatus is usually brought into contact with water such as in the wash box, and as a result the tar which separates from the gas is usually recovered in the form of an emulsion with water. The tar emulsion in extreme cases, may contain as high as 95% water or even higher. In some cases, the tar emulsion may be in the form of a pasty solid of very high viscosity. As a rule, the tar emulsion will contain at least 50% water and in this respect differs from tars obtained in processes for the production of coal gas or coke oven gas or in many oil cracking processes for the production of motor fuel, for in the latter processes the tar as recovered is not in an emulsion form. Therefore, the term "tar emulsion" or "petroleum tar emulsion" as used hereinafter and in the claims refer to emulsions of tar and water produced in the manner described, namely during the manufacture of combustible gas by processes involving the pyrolytic decomposition of petroleum oil.

The recovered mixture of tar and water from gas-making operations involving the decomposition of petroleum oil is usually first collected in a settling tank for the separation of as much water as possible by layer formation and decantation.

In accordance with prior art practice the relatively stable tar emulsion which remains after separation of the water layer has usually been treated according to some method of dehydration, such as centrifuging or distillation.

Centrifugal methods of treating tar emulsions, however, separate only the tar and the water of the emulsion and do not separate lighter tar constituents from the heavier. Furthermore, the presence of free carbon in the emulsion may give rise to operating difficulties.

The separation of the tar emulsion by ordinary distillation methods results in fractions which comprise (1) water, (2) a distillate from the tar comprising light oil and dead oil, and (3) residual tar.

For purposes of convenience in description, that portion of the distillate boiling up to approximately 200° C. (392° F.) at atmospheric pressure, will be designated "light oil" and that portion of the distillate boiling above approximately 200° C. at atmospheric pressure will be designated "dead oil." These may be separated from each other by distillation.

The light oil fraction contains, among other things, valuable saturated and unsaturated aromatic hydrocarbons such as benzene, toluene, xylene, styrene, methyl styrene, indene, etc.

The dead oil fraction contains naphthalene, methyl and other substituted naphthalenes, and 15 may contain anthracene, methyl anthracene, as well as numerous other hydrocarbons for the most part as yet unidentified.

The residual tar contains free carbon, pitch and other bitumens and usually contains constituents which are polymerizable.

The residual tar has a number of uses. For example, it may be used as a road tar or as a heavy liquid fuel. For both purposes, the viscosity of the residual tar is of importance, among other things, because of its effect upon the ease of handling.

Due to the fact that the tar is subjected to elevated temperatures for considerable lengths of time such as of the order of 10 to 16 hours in ordinary distillation procedures of the prior art for breaking emulsions and for the separation of light oil and dead oil as distillate, substantial polymerization is caused to take place. Such polymerization tends to reduce the quantity of distillate on the one hand and to increase the viscosity of the residual tar on the other, both of which are undesirable.

In copending application Serial Number 342,40 735, filed June 27, 1940 by Edwin L. Hall and Howard R. Batchelder, there is described and claimed a process for breaking tar emulsions with the recovery of light oil and substantial quantities of dead oil containing considerable quantities of 45 constituents in readily heat polymerizable state. In said process a tar emulsion is rapidly heated to an appropriate temperature capable of volatilizing considerable dead oil and then discharged into a separation zone which may be maintained 50 at any desired suitable pressure, such as atmospheric or subatmospheric. Thus a relatively large percentage of extremely heat sensitive unsaturated resin forming material is recovered in the dead oil fraction which is not the case in 55 prior art practice for in the latter practice these

materials are polymerized and left behind in the residual tar.

This invention is a modification of the invention described and claimed in said copending application and is directed to improvements in the separation of more volatile constituents from less volatile constituents.

The various features of the invention will become more apparent to persons skilled in the art as the description proceeds and upon reference to the drawing in which:

The figure is a flow sheet diagrammatically illustrating one form of the invention.

Referring now more particularly to the figure, 10 is a preheater for petroleum tar emulsion which enters through line 11 and leaves through line 12.

Line 12 leads to vaporizer 13 being connected to inlet 14 which as illustrated comprises a header which communicates with the lower ends of a plurality of up-pass tubes 15.

Up-pass tubes 15 at their upper ends communicate with the chamber 16.

Down-pass tubes 17 are connected to chamber 16 at their upper ends and with chamber 20 at their lower ends.

Shell 21 of vaporizer 13 surrounds the up-pass and down-pass tubes 15 and 17 forming a heat exchange chamber 22 for the flow of a heat exchange medium, such as steam, openings 23 and 24 being provided for the inlet and outlet of said heat exchange medium.

Chamber 20 is connected to a separating chamber 25 through a vapor line 26 and a liquid line 27 as illustrated.

Chamber 25 as illustrated is provided over its upper portion with phase contacting means 30. Phase contacting means 30 may be of any type and of any desired efficiency. However, I generally prefer to employ phase contacting means of a relatively open character and having hardly more than a few theoretically perfect plates.

It is to be understood, however, that phase contacting means 30 may be omitted or other means for the separation of high boiling constituents may be substituted therefor, such as means for the separation of entrained liquid particles, the purpose being to prevent or reduce the overhead travel of tar or other high colored liquid particles.

Vapor outlet 31 of chamber 25 is connected to inlet 32 of condenser 33.

Condenser 33 is conveniently cooled in a manner to generate steam for use in a second separating stage, if such is provided or for other purposes, although any type of condenser may be employed.

As illustrated, condenser 33 has an inlet 34 for water and an outlet 35 for generated steam, it being understood that condenser 33 is of the indirect heat exchange type.

Condensate outlet 36 of condenser 33 is connected to inlet 37 of cooler 40.

Outlet 41 of cooler 40 is connected to a decanter 42. Decanter 42 has an outlet 43 for the water layer and an outlet 44 for the hydrocarbon layer.

Outlet 44 of decanter 42 is connected through line 45 with a tank 46 from which a line 47 leads back to the upper portion of separating chamber 25.

Separating chamber 25 has a liquid outlet 58 which is connected by line 59 and pump 52 to line 53 which in turn is connected to line 11 through valve 54. Feed line 55 for petroleum tar emulsion is also connected to line 11.

The operation of the apparatus so far described is as follows.

Emulsion to be separated is fed through feed line 55 of the line 11 and into preheater 10 in which any desired quantity of preheat may be added to the emulsion to be separated.

Preheated emulsion flows through line 12 into vaporizer 13 in which the temperature is raised sufficiently to effect considerable vaporization such as of the order of 100° C. to 350° C.

10 The heated constituents ascend through up-pass tubes 15 and descend through down-pass tubes 17 into chamber 20 wherein at least a partial separation of vapor and liquid particles may take place, the vapor tending to pass through line 26 into separating chamber 25 and the liquid tending to pass through line 27 into separating chamber 25, although it is to be understood that some liquid and some vapor may pass through 20 the respective lines.

15 The rest of the separation of vapor from liquid takes place in separating chamber 25 which if provided with phase contacting means 30, may also be provided with down flowing reflux provided through line 47 from hydrocarbon collecting chamber 46, by pump 48.

20 The separation of the petroleum tar emulsion into its constituents takes place in a single stage however, the provision of hydrocarbon reflux for countercurrent contact with ascending vapors in the upper portion of chamber 25 may be omitted and baffles or other phase separating means may be substituted for phase contacting means 30, or the upper portion of chamber 25 may be relatively empty.

25 Separated vapors flow through outlet 31 to condenser 33 wherein as illustrated, the heat released upon condensation heats cooling water to such an extent as to generate steam therefrom, although it is to be understood that this is merely for the conservation of energy and that any other type of condenser might be substituted.

30 Depending upon the amount of condensation which takes place in condenser 33, the materials 40 which enter cooler 40 through inlet 37 may be wholly or only partially in the liquid phase, the function of cooler 40 being to cool the constituents to any desired lower temperature and preferably sufficiently to condense any uncondensed portion.

35 The condensate flows from cooler 40 into decanter 42 for separation by layer formation, water being withdrawn through line 43 and hydrocarbons through line 45. The reflux liquid when provided in separating chamber 25 is furnished conveniently from the hydrocarbons which collect in collecting chamber 46.

40 I find that it is especially advantageous from the standpoint of efficient separation of relatively volatile from relatively non-volatile constituents to cause the relatively non-volatile constituents to flow through the system at a relatively high rate.

45 I also find it to be especially advantageous to continuously recirculate relatively non-volatile constituents through the heating and separating zones at a relatively high rate. A very high efficiency of separation is thus obtainable and any tendency for high molecular weight tarry hydrocarbons and free carbon to separate and adhere to the walls of the system is very effectively overcome.

50 To effect this purpose any desired portion of the liquid drawn off from chamber 25 through line 51 may be recirculated through the heating and

separating zones through line 53 and valve 54, line 53 connecting to feed line 11, pump 52 being provided to maintain any desired rate of circulation.

Any desired portion of the non-vaporized constituents may be drawn off through valve 56 and line 57, untreated emulsion being fed in through line 55 to compensate therefor.

Any desired proportion of fresh feed stock to recirculated stock may be maintained such as, for example, from 1 to 1 or less to 1 to 50 or more, although I prefer to operate between 1 part of fresh feed stock to 10 parts of recycle stock to 1 part of fresh feed stock to 35 parts of recycle stock.

From the foregoing it will be seen that a rapid transit of the materials under treatment through the heating zone and into and through the separating zone is preferred.

As a result of my invention, a highly effective and satisfactory separation is made between residual tar and constituents which it is desired to remove therefrom and such separation may proceed at a very high rate.

Further more, the materials in process are more effectively heated and thus more effectively and efficiently separated since any tendency for the separation and adherence of highly non-volatile tar constituents to the heat exchange walls of the vaporizer is effectively overcome.

Furthermore, the very rapid rate of flow of liquid materials through the heater produces a high degree of turbulence and a very efficient heat exchange. Still further, the elimination of any tendency towards stream line flow prevents the overheating of a layer of material close to the heating surfaces with the consequent polymerization of very heat sensitive unsaturated material contained therein.

In accordance with my invention, tar emulsions may be dehydrated in a manner (1) such that the yield of dead oil therefrom may be increased at the expense of residual tar without encountering a corresponding increase in viscosity of the residual tar; or (2) such that for a given yield of dead oil a residual tar of lower viscosity is obtainable than by conventional methods. Furthermore, it is possible to obtain by my process a higher dead oil yield than is possible by conventional methods. Moreover it is possible to obtain by my process in the dead oil yield a relatively high percentage of extremely heat sensitive monomeric material which when employing conventional methods is polymerized to extremely non-volatile tar constituents which find their way into the residual tar instead of into the dead oil.

These highly heat sensitive dead oil constituents are very valuable from the standpoint of resin manufacture when separated in the dead oil fraction but are relatively of very little value when polymerized in the separation process to form residual tar.

Thus in the practice of my invention a tar emulsion is rapidly heated to an appropriate temperature and then discharged into a separation zone which may be maintained at any desired suitable pressure such as atmospheric or below under conditions such that (1) the vaporized portion may be rapidly separated and removed, and (2) the unvaporized portion is rapidly recirculated with a portion removed and preferably cooled to below polymerizing temperatures.

By such procedure, highly heat sensitive volatilized material in process does not remain at op-

erating temperatures for protracted periods prior to separation from the residual tar. Thus polymerization of highly heat sensitive volatile material while in contact with non-volatile material is very materially reduced with the result that a larger proportion of the original tar may be taken off overhead as distillate along with the water while processing the bottom or residual material to give the desired residual tar viscosity.

10 It will be understood that two factors effect residual tar viscosity, namely (1) the proportion of relatively fluid oils left in the residual tar which may be controlled by the proportion of volatile material removed overhead, and (2) the 15 proportion of unsaturated material polymerized into less volatile more viscous polymers.

It will be understood that a part of such unsaturated material may actually be so relatively non-volatile as to find its way into the residual tar in any event.

20 Since in the practice of my process when operating at temperature sufficiently high to seriously affect the highly heat sensitive constituents of the dead oil, such constituents are rapidly separated in vaporized form from the relatively non-volatile residual tar constituents, it follows that the residual tar from which a relatively large proportion of highly heat sensitive materials has been separated may be kept in process at elevated 25 temperatures for a considerably longer period of time without undue increase in viscosity, than is possible in conventional methods of tar dehydration. As a result it is possible in my process to continuously recirculate the residual tar through

30 the heating zone for a considerable period of time without too seriously effecting the residual tar viscosity and by virtue of such recirculation a relatively large proportion of the volatile constituents in the tar are afforded an opportunity 35 to vaporize and to be separated in vaporized form from the residual tar:

In my process, assuming that other things remain unchanged, item (1) preceding may be increased and decreased by decrease and increase in 40 the temperature to which the materials are subjected in the heating zone. However, consideration should be given to the effect of higher temperatures upon (2) preceding taken in conjunction with heating time. Since polymerization is 45 a function of both temperature and time the effect of higher temperatures during shorter heating times may be made the equivalent of the effect of lower temperatures during longer heating times. I find that a relatively wide range of 50 both temperature and heating time is afforded particularly when operating at atmospheric pressures and below, without losing the advantages of my method over conventional methods of tar dehydration. However, I prefer to maintain the 55 time during which the highly heat sensitive volatile material is heated while in contact with the relatively non-volatile constituents at a virtual minimum or at least relatively low in order to avoid the polymerization of such highly heat sensitive volatile material into relatively non-volatile 60 residual tar constituents.

65 Preferably the highly heat sensitive dead oil constituents are not subjected to temperatures of the order of 100° C. and above for longer than 70 ninety minutes with still shorter periods of heating still more preferable as above indicated.

75 Preferably also the tar residue is not subjected to heating longer than three hours with shorter periods still more preferred.

75 As previously stated however wide variations

may be made from such preferred periods while still securing advantages of my invention.

As pointed out previously, the process may be conducted in one or more stages. A two stage process is very convenient since this makes it possible to take overhead at atmospheric or near atmospheric pressures the more relatively volatile constituents such as water, benzene, toluene, xylene, styrene, methyl styrene and indene, which may be condensed at normal temperatures and the use of considerably reduced pressures for the removal of the less relatively volatile constituents such as those boiling above 200° C. and up to 350° C. and higher when at atmospheric pressure and to also condense these materials at ordinary temperatures. The use of considerably reduced pressures when removing materials such as benzene might require condenser temperatures sufficiently low to solidify a part of the condensate to cause condenser stoppages.

The use of considerably reduced atmospheric pressures in the separation of highly heat sensitive dead oil constituents is preferred since this in turn permits the use of considerably lower temperatures for a given separation than would be possible at higher pressures.

Referring again to the drawing, it will be noted that line 53 as shown connects through valve 58 to feed line 59 which in turn is connected to inlet 60 of a second stage vaporizer 61.

Second stage vaporizer 61 may be in all respects similar to first stage vaporizer 13 and as shown is connected to a second stage separating chamber 62 in the same manner as first stage separating chamber 25 is connected to first stage vaporizer 13. Thus vaporizer 61 and separating chamber 62 may if desired have substantially the same design and construction as vaporizer 13 and separating chamber 25 respectively and may be connected together in substantially the same manner.

Vapor outlet 63 of chamber 62 leads to condenser 64 which in turn is connected through line 65 to a condensate receiver 66.

As illustrated, a vacuum line 67 for maintaining the desired reduced pressure in separating chamber 62 is connected to receiver 66. Vacuum line 67 is connected to pump 70 which discharges into a decanter 71 for separation of water through outlet 72 from hydrocarbon condensate through outlet 73.

Since the hydrocarbon condensate separated in the second stage is of a density similar to that of water and changes more rapidly with change in temperature than water, under certain conditions the outlets for water and hydrocarbon condensate at decanter 71 might be reversed.

Liquid outlet 74 at the bottom of chamber 62 connects with line 75 which leads to pump 76, one outlet of which connects with line 77, provided with valve 78, which in turn connects with line 59. The other outlet of pump 76 connects with line 79, provided with valve 80, which may lead to storage or to any other suitable point.

The operation of the process in two stages may be described as follows.

The first stage may operate in all respects similar to that already described with the exception that a lesser portion of the volatile material from the tar is taken overhead in the first stage.

For example, the material taken overhead in the first stage might be comprised preponderately of constituents which boil for the most part below say 200° C., when at atmospheric pressure, with

a relatively small proportion of materials boiling above say 200° C., when at atmospheric pressure.

The residual tar from this stage may then contain the preponderate part of the dead oil constituents. All or any desired portion of this tar may be passed through line 53, valve 58 and line 59 into second stage vaporizer 61 wherein it is heated preferably under vacuum to an appropriate temperature to volatilize a substantial quantity of the dead oil constituents therein. Liquid and vaporized constituents flow from vaporizer 61 into separator 62 wherein volatilized constituents are separated from non-volatilized constituents and taken overhead to condenser 64 wherein they are condensed and collected in receiver 66 from which they flow through vacuum line 67, pump 70 into decanter 71 for the separation of hydrocarbon condensate from any water which might be present.

If desired, separating chamber 62 may be provided with baffles or any other means to prevent entrained non-volatilized tar particles from passing overhead with the vaporized constituents.

Non-vaporized liquid flows from separating chamber 62 through line 75, pump 76, line 77 to line 59 back to and through heater 61 and separating chamber 62.

The proportion of recirculated stock to incoming tar stock from the first stage may be maintained at any desired level, for example the same as described in connection with the single stage.

Likewise, in the first stage the proportion may be the same as described in the single stage operation.

Residual tar is drawn off from pump 76 through line 79 and may flow to storage or to any other desired point.

If desired the partial pressures of the vaporized hydrocarbons in vaporizer 13, separating chamber 25, vaporizer 61, separating chamber 62, etc., may be reduced by the addition of suitable gas, such as stripping steam. For example stripping steam may be introduced into vaporizer 61 and means for this purpose is illustrated at 81 which comprises a steam line leading from outlet 35 of condenser 33 to inlet 82 at the top of the vaporizer 61.

When a two stage process is employed it is sometimes preferable to separate substantially all of the dead oil constituents in the second stage. To reduce the quantity of dead oil separated in the first stage it is frequently desirable to provide sufficient reflux in the first stage and sufficient phase contact in separator 25 to scrub out constituents from the vapor which boil above say 200° C. or 210° C., or at any other chosen cut point.

The two stage process with the recycle of tar in one or both stages and particularly in both stages is a highly efficient method for the separation of a petroleum tar emulsion into its constituents as illustrated by the following example.

Example 1

Petroleum oil tar emulsion, containing approximately 37 per cent water and having a specific gravity of approximately 1.02, was dehydrated in a two stage apparatus similar to that described above.

The emulsion was fed to the first vaporizer still at a rate of approximately 10 gallons per minute and heated therein to approximately 100° C. at approximately atmospheric pressure.

The heated material was led from the first stage vaporizer to the first stage separation zone and

the vaporized and unvaporized constituents separated therein, at substantially atmospheric pressure, the vaporized material being taken off overhead, and the unvaporized being taken off from the separating chamber as bottoms.

80 per cent of the water in the emulsion fed to the vaporizer was taken off overhead from the first stage, together with a quantity of hydrocarbon material equal to approximately 0.19 pounds per pound of dry tar fed to the vaporizer in the form of emulsion, approximately 94 per cent of this hydrocarbon material was comprised of light oil constituents and approximately 6 per cent was comprised of dead oil constituents.

The bottoms from the first separation stage was comprised of the remainder of the water, approximately one-third of the light oil, the bulk of the dead oil and substantially all of the residual tar constituents contained in the original emulsion.

A portion of these bottoms led off from the first stage separation chamber was recycled to the first stage vaporizer, at a rate of approximately 250 to 300 gallons per minute.

The remainder of the bottoms from the first separation stage was fed to the vaporizer of the second stage and heated therein to approximately 145° C.

The heated material was led to the second stage separation zone which together with the second stage vaporizer was maintained at a pressure of approximately 100 mm. Hg. absolute and the vaporized and unvaporized materials were separated therein.

The vaporized material was passed upward through the separation chamber and was taken off as overhead. The unvaporized material was passed downward and was taken off as bottoms.

The overhead material from the second stage separation contained the remaining 20 per cent of the water contained in the original emulsion together with a quantity of hydrocarbon material equal to approximately 0.36 pound per pound of dry tar in the original emulsion fed to the first stage.

The overhead material from the second stage separation also contained the water supplied to the second stage in the form of stripping steam, which was employed in quantity equal to approximately 0.5 pound per pound of dry tar fed to the first stage still in emulsion form.

Of the hydrocarbon material taken off overhead from the second stage, approximately 27 per cent was comprised of light oil constituents and approximately 73 per cent was comprised of dead oil constituents, associated with small quantities of entrained unvaporized residual tar constituents.

The bottoms from the second stage separation was comprised of dry residual tar, which was divided into two streams. One stream was led off as product. The other stream was recycled to the second stage vaporizer at a rate of approximately 250 gallons per minute.

Separated dry residual tar having a viscosity of approximately 4000 S. S. U. at 210° F. was recovered in quantity equal to approximately 0.45 pound per pound of dry tar in the emulsion fed to the first stage.

Light oil from the two stages totaled approximately 0.27 pound per pound of dry tar in the emulsion fed to the first stage.

Dead oil from the two stages totaled approximately 0.28 pound per pound of dry tar in the emulsion fed to the first stage.

The time the dead oil constituents were exposed to elevated temperatures of the order of 100° C. and above in the operation was of the order of 57 minutes.

5 The time the tar residue was exposed to temperatures of the order of 100° C. and above was of the order of 150 minutes.

10 The dead oil contained approximately 23% of readily heat polymerizable unsaturated resin-forming material which upon heat polymerization readily yielded a valuable resin.

15 It will be noted that the temperatures employed in the first stage are very low in the bracket of from 100° C. to 350° C. which was given as an example of a range in temperatures and that the temperatures employed in the second stage are somewhat higher in this bracket.

20 It will be understood that the temperatures given are purely for example. If sub-atmospheric pressures are employed in the first stage, the temperature in the first stage may be below 100° C.

25 Preferably the temperatures in the first stage, when no dead oil constituents or only a relatively small proportion of the dead oil constituents are taken off overhead, do not exceed approximately 120° C. This is because a large proportion of the dead oil is recycled along with the residual tar in this stage and it is of course desired to avoid a large degree of polymerization of the highly heat sensitive constituents in the dead oil.

30 In the second stage which is operated at a higher temperature (and at a lower pressure) the dead oil is taken overhead immediately upon vaporization and separation from the residual tar. Thus in this stage recirculation of the residual tar does not increase the quantity of highly heat sensitive dead oil constituents polymerized into non-volatile constituents but actually affords an opportunity for any non-volatilized dead oil constituents to be separated from the residual tar during the recycle thereof.

35 Since the highly heat sensitive dead oil constituents are rapidly separated from the residual tar in the second stage the residual tar may be recycled without danger of reaching an excessively high residual tar viscosity.

40 While temperatures in the second stage may reach as high as 350° C., I prefer to operate with a sufficiently high vacuum in the second stage such that the desired proportion of dead oil may be taken off overhead with temperatures which do not substantially exceed 160° C.

45 While particular apparatus has been described in connection with the process it is to be understood that this is subject to considerable variation and different forms of apparatus and design are within the skill of an experienced engineer.

50 It will also be understood that the process is subject to considerable variation.

55 More than two stages may be employed if desired and any desired division may be made as to the materials taken off overhead and as bottoms from the various stages.

60 When employing two or more stage it may be preferred to remove substantially all of the water in the first stage feeding substantially dry tar to the second stage, on the other hand only a portion of the water may be removed in the first stage.

65 It may also be preferred to take off substantially no dead oil overhead from the first stage, for example all of the dead oil recovered being taken off overhead from the second stage.

70 75 If only one stage is employed it may be desired

to admit a gaseous stripping agent to vaporizer 13, and it may be desired to employ a gaseous stripping agent in the first stage as well as in succeeding stages when more than one stage is employed. The use of a gaseous stripping agent, such for example as steam, in the single stage or in the first stage of a plurality of stages is particularly desirable if the proportion of water in the petroleum tar-water emulsion treated is low.

It may be desirable also to vary the quantity of stripping agent supplied to succeeding stages in accordance with the water content of the material supplied to such stages.

Any desired means may be provided for heating preheater 10 and the vaporizers 13 and 61 such as firing by solid or fluid fuel, though heating by steam may be preferred from the standpoint of securing more uniform heating.

It may be preferred to maintain a uniform feed of emulsion to the apparatus and to that end it may be preferred to provide a suitable storage tank for the emulsion, provided with agitating means such as a stirrer, to prevent stratification and consequent rapid variation in the water content of the emulsion fed to line 55.

In the drawing the material recycled in any stage flows through the entire heating zone in admixture with the feed to that heating zone. The recycled material might be united with the feed after the feed had already passed through a portion of the heating zone.

Other modifications will readily occur to those skilled in the art.

The term "comprising" is employed in the claims in its generally accepted meaning and does not exclude the presence of steps and materials other than those recited.

Therefore, changes, omissions, additions, substitutions and/or modifications may be made within the scope of the claims without departing from the spirit of the invention which is limited only as required by the prior art.

I claim:

1. In a process for the dehydration of a petroleum tar-water emulsion with the separation of the constituents of the tar into tar residue and hydrocarbon distillate with decreased polymerization of heat polymerizable unsaturated hydrocarbon material contained in said tar, the steps comprising rapidly vaporizing constituents including water and unsaturated monomeric hydrocarbon dead oil constituents contained in a stream comprising said petroleum tar-water emulsion, separating vaporized constituents including unsaturated monomeric dead oil material from unvaporized constituents, and recycling a portion of the separated unvaporized constituents for admixture in said stream with said petroleum tar-water emulsion undergoing vaporization of constituents thereof.

2. In a process for the dehydration of a petroleum tar-water emulsion with the separation of the constituents of the tar into tar residue and hydrocarbon distillate with increased recovery in said hydrocarbon distillate of the heat polymerizable unsaturated hydrocarbon material contained in said tar and which boils above 200° C. when at atmospheric pressure, the steps comprising rapidly vaporizing constituents including water and hydrocarbon constituents boiling above 200° C. when at atmospheric pressure contained in a stream comprising said petroleum tar-water emulsion, separating vaporized constituents from unvaporized constituents, and recycling a portion of the separated unvaporized constituents for ad-

mixture in said stream with said petroleum tar-water emulsion undergoing vaporization as to constituents thereof, said vaporization and separation being carried out with sufficient rapidity to separate in heat polymerizable form and as a part of said vaporized constituents a considerable portion of said heat polymerizable unsaturated hydrocarbon material boiling above 200° C. when at atmospheric pressure.

3. In a process for the dehydration of a petroleum tar-water emulsion with the separation of the constituents of the tar into tar residue and hydrocarbon distillate with decreased polymerization of heat polymerizable unsaturated hydrocarbon material contained in said tar, the steps comprising rapidly heating a stream comprising said petroleum tar-water emulsion in a heating zone, flowing the resulting heated material into a separating zone for the separation therein of vaporized constituents including unsaturated monomeric dead oil material from unvaporized constituents including tar residue, after separation removing said vaporized constituents including unsaturated monomeric dead oil material, after separation removing said unvaporized constituents, and recycling a portion of said removed unvaporized constituents to said heating zone for passage through at least a part thereof in admixture with said petroleum tar-water emulsion in said stream, the proportion of recycle stock to fresh feed stock being at least as high as 1 part of recycle stock to 1 part of fresh feed stock.

4. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, said petroleum tar-water emulsion having been previously treated to reduce its content of material boiling below 200° C. when at atmospheric pressure, the steps comprising rapidly heating a stream comprising said petroleum tar-water emulsion in a heating zone to a temperature sufficiently high under the pressure conditions obtaining to vaporize water and hydrocarbon constituents of said tar boiling above 200° C. when at atmospheric pressure including heat polymerizable unsaturated hydrocarbon material boiling above 200° C. when at atmospheric pressure, flowing the resulting heated material into a separating zone for the separation therein of vaporized constituents from unvaporized constituents, after separation removing said vaporized constituents including heat polymerizable unsaturated hydrocarbon material boiling above 200° C. when at atmospheric pressure, after separation removing said unvaporized constituents, and recycling a portion of said removed unvaporized constituents to said heating zone for passage through at least a part thereof in admixture with said petroleum tar-water emulsion in said stream, said vaporization and separation being carried out with sufficient rapidity to separate in heat polymerizable form and as a part of said vaporized constituents a considerable portion of said heat polymerizable unsaturated hydrocarbon material boiling above 200° C. when at atmospheric pressure.

5. In a process for the dehydration of a petroleum tar-water emulsion with separation of the constituents of the tar into tar residue and hydrocarbon distillate with increased recovery in said hydrocarbon distillate of heat polymeriza-

ble unsaturated hydrocarbon material contained in said tar and which boils above 200° C. when at atmospheric pressure, the steps comprising rapidly flowing a stream comprising said petroleum tar-water emulsion through a heating zone at a rate of flow sufficient to produce a high degree of turbulence and rapidly heating said stream therein sufficiently under the pressure conditions obtaining to vaporize water and hydrocarbon constituents boiling below 200° C. when at atmospheric pressure, rapidly separating the resulting vaporized and unvaporized constituents, recycling a portion of said separated unvaporized constituents to said heating zone for passage through at least a part thereof in admixture with said petroleum tar-water emulsion in said stream, rapidly flowing a stream comprising another portion of said separated unvaporized constituents through a second heating zone at a rate of flow sufficient to produce a high degree of turbulence and rapidly heating said second named portion of unvaporized constituents therein sufficiently under the pressure conditions obtaining to vaporize hydrocarbon constituents thereof boiling above 200° C. when at atmospheric pressure, rapidly separating vaporized constituents produced by said heating in said second heating zone from unvaporized constituents, and recycling a portion of said last named unvaporized constituents to said second heating zone for passage through at least a part thereof in admixture with said second named portion of unvaporized constituents, said vaporizations and separations being carried out sufficiently rapidly to separate in heat polymerizable form and as a part of said second mentioned vaporized constituents a considerable portion of said heat polymerizable unsaturated hydrocarbon material boiling above 200° C. when at atmospheric pressure.

6. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps comprising rapidly heating in a heating zone a highly turbulent stream comprising said petroleum tar-water emulsion to a temperature sufficiently high under the pressure conditions obtaining to vaporize water and hydrocarbon constituents of said tar boiling below 200° C. when at atmospheric pressure but not sufficiently high to vaporize a preponderant portion of the volatile constituents contained in said tar which boil between 200° C. and 350° C. when at atmospheric pressure, flowing the resulting heated material into a separating zone for the separation therein of vaporized constituents from unvaporized constituents, after separation removing said vaporized constituents from said separating zone, after separation removing said unvaporized constituents from said separating zone, recycling a portion of said removed unvaporized constituents to said heating zone for highly turbulent passage through at least a part thereof in admixture with said petroleum tar-water emulsion in said stream, rapidly heating in a second heating zone a highly turbulent stream comprising another portion of said removed unvaporized constituents to a temperature sufficiently high under the pressure conditions obtaining to vaporize a substantial portion of the volatile constituents thereof boiling between 200°

C. and 350° C., flowing the heated material resulting from said second heating step into a second separating zone for the separation therein of vaporized constituents from unvaporized constituents, removing said last named vaporized constituents from said second separating zone, removing said last named unvaporized constituents from said separating zone, and recycling a portion of said last named removed unvaporized constituents to said second heating zone for highly turbulent passage through at least a part thereof in admixture with said second named stream.

7. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps comprising rapidly heating a stream comprising said petroleum tar-water emulsion in a heating zone to a temperature sufficiently high under the pressure conditions obtaining to vaporize water and light oil constituents thereof, flowing the resulting heated material into a separating zone for the separation therein of vaporized constituents from unvaporized constituents, after separation removing vaporized constituents from said separating zone through phase contacting means, thereafter condensing removed vaporized constituents returning a portion of the resulting hydrocarbon condensate to said phase contacting means as reflux for the condensation therein of relatively less volatile constituents in said vaporized constituents removed therethrough, after separation recycling a portion of said unvaporized constituents together with at least a portion of said relatively less volatile constituents condensed from said vaporized constituents to said heating zone for passage through at least a part thereof in admixture with said petroleum tar-water emulsion in said stream, after separation rapidly heating a stream comprising another portion of said unvaporized constituents in a second heating zone to a temperature sufficiently high under the pressure conditions obtaining to vaporize dead oil constituents thereof, flowing the resulting heated material into a second separating zone for the separation therein of vaporized constituents from unvaporized constituents, after separation removing said last named vaporized constituents after separation removing said last named unvaporized constituents, and recycling a portion of said last named unvaporized constituents to said second heating zone for passage through at least a part thereof in admixture with said last named stream.

8. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps comprising rapidly heating a stream comprising said petroleum tar-water emulsion together with an added gaseous diluent in a heating zone to a temperature sufficiently high under the pressure conditions obtaining to vaporize water and hydrocarbon constituents boiling above 200° C. when at atmospheric pressure, flowing the resulting heated material into a separating zone for the sep-

aration therein of vaporized constituents from unvaporized constituents, after separation removing said vaporized constituents from said separating zone, after separation removing said unvaporized constituents from said separating zone, and recycling a sufficient portion of said unvaporized constituents to said heating zone for passage through at least a part thereof in admixture with said petroleum tar-water emulsion in said stream to produce a highly turbulent flow of said admixture.

9. In a process for the dehydration of a petroleum tar-water emulsion with the separation of the constituents of the tar into tar residue and hydrocarbon distillate with decreased polymerization of heat polymerizable unsaturated hydrocarbon material contained in said tar, the steps comprising rapidly heating a stream comprising said petroleum tar-water emulsion in a heating zone to a temperature sufficiently high under the pressure conditions obtaining to vaporize water and hydrocarbon constituents thereof, flowing the resulting heated material into a separating zone for the separation therein of vaporized constituents from unvaporized constituents, after separation removing said vaporized constituents, after separation removing said unvaporized constituents, rapidly heating a stream comprising at least a portion of said removed unvaporized constituents in a second heating zone to a temperature sufficiently high under the pressure conditions obtaining to vaporize hydrocarbon constituents thereof which boil above 200° C. when at atmospheric pressure, flowing the resulting heated material into a second separating zone for the removal therein of vaporized constituents from unvaporized constituents, removing said last named vaporized constituents from said second separating zone, removing said last named unvaporized constituents from said second separating zone, and recycling a portion of the unvaporized constituents removed from at least one of said separating zones to the preceding heating zone for passage through at least a part thereof in admixture with the stream heated therein to produce a highly turbulent flow of said admixture in the said preceding heating zone.

10. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps comprising heating rapidly a stream comprising said petroleum tar-water emulsion in a heating zone to a temperature sufficiently high under the pressure conditions obtaining to vaporize water and hydrocarbon constituents of said tar which boil below 200° C. when at atmospheric pressure, flowing the resulting heated material into a separating zone for the separation therein of vaporized constituents from unvaporized constituents, removing said vaporized constituents from said separating zone, removing said unvaporized constituents from said separating zone, rapidly heating a stream comprising at least a portion of said removed unvaporized constituents in a second heating zone at reduced pressure and to a temperature sufficiently high under the pressure conditions obtaining to vaporize constituents thereof which boil above 200° C. when at atmospheric pressure, flowing the resulting heated material into a second separating zone for the separation therein of

5 vaporized constituents from unvaporized constituents, removing vaporized constituents from said second separating zone, removing unvaporized constituents from said second separating zone, and recycling a portion of the unvaporized constituents removed from at least one of the said separating zones to the preceding heating zone for passage through at least a part thereof in admixture with said stream heated therein, said vaporizations and separations being effected with sufficient rapidity to separate in heat polymerizable form and as a part of said second mentioned vaporized constituents a considerable portion of said heat polymerizable unsaturated hydrocarbon material boiling above 200° C. when at atmospheric pressure.

11. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps comprising rapidly heating a rapidly flowing stream comprising said petroleum tar-water emulsion in a heating zone to a temperature sufficiently high under the pressure conditions obtaining to vaporize water and hydrocarbon constituents thereof which boil below 200° C. when at atmospheric pressure, flowing the resulting heated material into a separating zone for the separation therein of vaporized constituents from unvaporized constituents, after separation removing vaporized constituents from said separating zone, after separation removing unvaporized constituents from said separating zone, recycling a portion of said removed unvaporized constituents to said heating zone for passage through at least a part thereof in admixture with said petroleum tar-water emulsion in said rapidly flowing stream, rapidly heating a stream comprising another portion of said removed unvaporized constituents in a second heating zone at reduced total pressure and in the presence of an added gaseous diluent and to a temperature sufficiently high under the pressure conditions obtaining to vaporize constituents thereof boiling above 200° C. when at atmospheric pressure, flowing the resulting heated material from said second heating zone into a second separating zone for the separation therein of vaporized constituents from unvaporized constituents, removing said last named vaporized constituents from said second separating zone, removing said last named unvaporized constituents from said second separating zone, and recycling a portion of said last named removed unvaporized constituents to said second heating zone for passage through at least a part thereof in admixture with said last named stream, said vaporizations and separations being effected with sufficient rapidity to separate in heat polymerizable form and as a part of said second mentioned vaporized constituents a considerable portion of said heat polymerizable unsaturated hydrocarbon material boiling above 200° C. when at atmospheric pressure.

12. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, said petroleum tar-water

emulsion having been previously treated to remove a large part of its hydrocarbon content boiling below 200° C. when at atmospheric pressure, the steps of rapidly flowing a stream of said petroleum tar-water emulsion through a heating zone and heating said stream therein to a temperature between approximately 100° C. and 350° C. and sufficiently high under the pressure conditions obtaining to vaporize water and hydrocarbon constituents of said tar boiling above 200° C. when at atmospheric pressure including heat polymerizable unsaturated hydrocarbon material boiling above 200° C. when at atmospheric pressure, flowing the resulting heated material without large pressure drop into a separating zone maintained at reduced pressure for the separation therein of vaporized constituents from unvaporized constituents, after separation removing said vaporized constituents including heat polymerizable unsaturated hydrocarbon material boiling above 200° C. when at atmospheric pressure, after separation removing said unvaporized constituents, and recycling a portion of said removed unvaporized constituents to said heating zone for passage through at least a part thereof in admixture with said petroleum tar-water emulsion in said stream, said admixture being passed through said heating zone with sufficient rapidity to produce highly turbulent flow, and said vaporization and separation being effected sufficiently rapidly to separate in heat polymerizable form and as a part of said vaporized constituents a considerable portion of said heat polymerizable unsaturated hydrocarbon material boiling above 200° C. when at atmospheric pressure.

13. In a process for the dehydration of a petroleum tar-water emulsion with separation of the constituents of the tar into tar residue and hydrocarbon distillate with increased recovery in said hydrocarbon distillate of heat polymerizable unsaturated hydrocarbon material contained in said tar and which boils above 200° C. when at atmospheric pressure, the steps of rapidly flowing a stream of said petroleum tar-water emulsion through a heating zone and rapidly heating said stream therein at a temperature between approximately 100° and 350° C. and sufficiently under the pressure conditions obtaining to vaporize water and hydrocarbon constituents boiling below 200° C. when at atmospheric pressure, flowing the resulting heated material without large pressure drop into a separating zone maintained at approximately atmospheric pressure and therein separating the resulting vaporized and unvaporized constituents, producing a highly turbulent flow of material in said heating zone by recycling a portion of said separated unvaporized constituents to said heating zone for passage through at least a part thereof in admixture with said petroleum tar-water emulsion in said stream, rapidly flowing a stream of another portion of said separated unvaporized constituents through a second heating zone and rapidly heating said second mentioned portion of unvaporized constituents therein at a temperature between approximately 100° and 350° C. and sufficiently under the pressure conditions obtaining to vaporize hydrocarbon constituents thereof boiling above 200° C. when at atmospheric pressure, flowing the resulting heated material without large pressure drop into a separating zone maintained at reduced pressure, and therein separating vaporized constituents produced by said heating in said second heating zone from unvaporized constituents, and

producing a highly turbulent flow of material in said second heating zone by recycling a portion of said last mentioned unvaporized constituents to said second heating zone for passage through at least a part thereof in admixture with said second mentioned portion of unvaporized constituents, said vaporizations and separations being carried out with sufficient rapidity to separate in heat polymerizable form and as a part of said last mentioned vaporized constituents a considerable portion of said heat polymerizable unsaturated hydrocarbon material boiling above 200° C. when at atmospheric pressure.

14. In a process for the dehydration of a petroleum tar-water emulsion with the separation of the constituents of the tar into tar residue and hydrocarbon distillate with increased recovery in said hydrocarbon distillate of heat polymerizable unsaturated hydrocarbon material contained in said tar and which boils above approximately 200° C. when at atmospheric pressure, the steps of rapidly heating a stream comprising said petroleum tar-water emulsion in a heating zone to a temperature not exceeding approximately 120° C. but sufficiently high under the pressure conditions obtaining to vaporize water and hydrocarbon constituents thereof which boil below 200° C. when at atmospheric pressure, flowing the resulting heated material without large pressure drop into a separating zone maintained at approximately atmospheric pressure for the separation therein of vaporized constituents from unvaporized constituents, after separation removing vaporized constituents from said separating zone, after separation removing unvaporized constituents from said separating zone, producing highly turbulent flow in said heating zone by recycling a portion of said removed unvaporized constituents to said heating zone for passage through at least a part thereof in admixture with said petroleum tar-water emulsion in said stream, rapidly heating a stream comprising another portion of said removed unvaporized constituents in a second heating zone to a temperature not exceeding approximately 160° C. but sufficiently high under the pressure conditions obtaining to vaporize constituents thereof boiling above 200° C. when at atmospheric pressure, flowing the resulting heated material from said second heating zone without large pressure drop into a second separating zone maintained under reduced pressure at least as low as 100 mm. Hg. for the separation therein of vaporized constituents from unvaporized constituents, removing said last mentioned vaporized constituents from said second separating zone, removing said last mentioned unvaporized constituents from said second separating zone, and producing highly turbulent flow in said second heating zone by recycling a portion of said last mentioned unvaporized constituents to said second heating zone for passage through at least a part thereof in admixture with said second mentioned stream, said vaporization steps and said separation steps being carried out with sufficient rapidity to separate in heat polymerizable form and as a part of said last mentioned vaporized constituents a considerable portion of said heat polymerizable unsaturated hydrocarbon material boiling above 200° C. when at atmospheric pressure.

15. In a process for the dehydration of a petroleum tar-water emulsion with the separation of the constituents of the tar into tar residue and hydrocarbon distillate with increased recovery in said hydrocarbon distillate of heat polymerizable

unsaturated hydrocarbon material contained in said tar and which boils above 200° C. when at atmospheric pressure, the steps of rapidly flowing a stream comprising said petroleum tar-water emulsion through a heating zone and rapidly heating said stream therein to a temperature sufficiently high under the pressure conditions obtaining to vaporize water and hydrocarbon constituents boiling below 200° C. when at atmospheric pressure, flowing the resulting heated material without large pressure drop into a separating zone and therein separating vaporized constituents from unvaporized constituents, producing a high degree of turbulence in the flow of material through said heating zone by recycling a portion of said separated unvaporized constituents to said heating zone for passage through at least a part thereof in admixture with said petroleum tar-water emulsion in said stream, rapidly flowing a stream comprising another portion of said unvaporized constituents through a second heating zone and rapidly heating said second mentioned stream therein in the presence of added steam to a temperature between approxi-

15 mately 100° and 350° C. and sufficiently under the pressure conditions obtaining to vaporize hydrocarbon constituents thereof boiling above 200° C. when at atmospheric pressure, flowing the resulting heated material from said second heating zone without large pressure drop into a second separating zone maintained at reduced pressure and therein separating vaporized constituents produced by said heating in said second heating zone from unvaporized constituents, and producing a high degree of turbulence in the flow of material through said second heating zone by recycling a portion of said last mentioned unvaporized constituents to said second heating zone for 20 passage through at least a part thereof in admixture with said second mentioned stream, said vaporizations and separations being carried out sufficiently rapidly to separate in heat polymerizable form and as a part of said second mentioned vaporized constituents a considerable portion of said heat polymerizable unsaturated hydrocarbon material boiling above 200° C. when at atmospheric pressure.
